JACOB GUTEKUNST, OF AUGSBURG, GERMANY.

CLOCK STRIKING MECHANISM.

SPECIFICATION forming part of Letters Patent No. 664,404, dated December 25, 1900.

Application filed April 19, 1898. Serial No. 678,182. (No model.)

To all whom it may concern:

Be it known that I, JACOB GUTEKUNST, a subject of the German Emperor, residing at Augsburg, in the Empire of Germany, have 5 invented certain new and useful Improvements in Clock Mechanism, of which the following is a full, clear, and exact specification.

The subject of the present invention is a quarter-strike movement with hour-repeating mechanism, which repeats the quarter at will from a certain time before the quarter. Both the hour-repeating mechanism at the quarter-strokes and the striking-train can be completely stopped, while, nevertheless, repeating remains possible by pulling a cord. 15 This striking-work is represented in the accompanying drawings, in which--

Figure 1 is a front view of the striking mechanism. Fig. 2 is a plan view. Fig. 3 is 20 a side view looking from the left. Fig. 4 is a detail showing the parts situated between the plates. Fig. 5 is a side view looking from the right. Fig. 6 is a bottom view. Figs. 7 and 8 are details. Figs. 9, 10, and 11 are further details illustrating the arrangement for 25 securing the quarter-strike, notwithstanding previous repetition by hand.

On the center arbor *a* are set the quarter-snail *b* and the hour-snail *c*. This arbor carries the piece *d* with four arms, which actuates the rack-hook *l* by means of these arms. Of one piece with the quarter-snail *b* or fixedly connected with same is a four-leaved pinion *e*, which is intended to engage into a star-wheel *f*, situated under the pinion *e*. The second star-wheel is maintained in its position by a detent *g*, which is pressed by a spring *g'*.

The hour-rack *h* and the quarter-rack *i* are 40 pivoted at *k*, and each of them carries an arm *h'* *i'*, respectively, by which the fall of the racks is limited in accordance with the position of the snails. The quarter-rack rests directly upon the periphery of the segmental end of the rack-hook *l*, while the hour-rack rests upon a pin *l'*, extending laterally from said end. The rack-hook *l* is pivoted at *l''* and is always pressed toward the rack by means of a spring *l''*. This hook carries at 45 its front side a pin *l''* and at its back two pins *m'* and *m''*, which render the full stroke of the last quarter and of the hour possible in the

manner described hereinafter. Between the rack-hook and the snail a lever is arranged pivoted at *n* and having three arms *n'* *n''* *n'''*. 55 The arm *n'* rests upon a pin *n''*, and the arm itself carries a pin *n'''*, which effects the release of the arrested hour-rack, when repeating takes place, as will be hereinafter described. The arm *n''* reaches as far as the rack-hook and acts upon it for bringing about repeating by hand, while a cord is attached on the arm *n'''*, which cord is adapted to be pulled to actuate the mechanism to produce the repetition. On the arm *n'''* of said three- 65 armed lever a second lever is pivoted at *o*, having three arms *o'* *o''* *o'''*, which is actuated by means of the arm *o'*, being operated upon by an arm of the piece *d*, and so influences the rack-hook. A spring *o''* tends to hold this 70 lever in normal position by pressing on the arm *o''*. The arm *o'''* carries an angle-lever having arms *p'* *p''*, pivoted at *p*. The shape of the arms of this angle-lever is shown in Fig. 1. The arm *p'* of this angle-lever pos- 75 sses a nose which acts in conjunction with the pin *l''*, carried by the rack-hook, while the arm *p''* is actuated by the gathering pallet or tumbler.

The gathering pallet or tumbler is arranged 80 on the tumbler-arbor *q* and carries two pins or noses *q'* and *q''*, diametrically arranged, which are in the position shown in Fig. 1 when the striking-work is arrested, each of which lifts one of the racks *h* *i*. In this lifting operation the forward pin *q'* actuates simultaneously the arm *p''*, before mentioned, while the rear pin *q''*, which lifts the quarter-rack, actuates also the arm *m* to be described.

In order to prevent hour-repeating in the 85 first, second, and third quarters, a lever having two arms *r'* *r''*, pivoted at *r*, is provided, the arm *r'* thereof having a hook-shaped end. The hour-rack *h* is extended past its pivot *k* and carries at the extremity of this extension 90 *h''* a pin *h'''*, adapted to be engaged by the hook of the arm *r'* to hold the rack *h* and prevent its falling. In order to repeat the hours at the stroke of the fourth quarter, this connection is broken by lifting the arm *r''* automatically by the pins *f'* of the star-wheel *f*. 95 This connection can also be broken when a repeat of the hour is desired, which is obtained by pulling the cord before mentioned,

which will tilt the lever pivoted at n and bring the pin n^5 of the arm n' into engagement with said arm r^2 and lift the same. A spring r^3 is provided, which tends to press the arm r' toward the pin h^3 . A pivoted piece s makes it possible to throw the lever having arms $r' r^2$ out of operation, Fig. 1, by means of a pin carried by said piece engaging with the arm r' , so that the hours are repeated at 5 every quarter. A pivoted piece s' throws out the whole striking mechanism by engaging with and raising the arm p' , before mentioned, out of the reach of the pin l^4 of the rack-hook l . The rack-hook l is fixed to the harbor l^2 , 10 which also has an arm having forked members $t' t^2$ fixed thereto. This arm is arranged between the plates and is for the purpose of throwing out the hammers which are inactive. Both members $t' t^2$ of this arm carry a pin t^3 15 of which the one t^3 lifts the hour-hammer and the other, t^4 , the quarter-hammers (according to the position of the snail) out of reach of the pins u , which actuate same, said pins being carried by one of the intermediate 20 wheels u' , which is geared to the fly v .

The hammers are attached behind the second plate and are secured to the arbors $w w'$ w^2 . By turning these arbors by means of the arms $x x' x^2$, fixed to the same, which are operated by the slide-bars $y y' y^2$ when pushed by the pins u , the hammers are lifted. The slide-bars rest on a bolt t . The quarter-hammers have toes z , upon which the pin t^4 acts. 25

The action of the striking-work is as follows: 30 As the center arbor a turns, the piece d , fixed thereon, turns also, bringing one of its arms into engagement with the arm o' of the lever pivoted at o . This arm is pressed down, tilting the lever and moving the arm o^3 toward 35 the left, as viewed in Fig. 1. The angle-lever, having the arms $p' p^2$, which is carried on this arm, is pulled back until the nose of the arm p' reaches a position behind the pin l^4 , fixed to the rack-hook l . As soon as the 40 arm of the piece d slides off of the arm o' the spring o^4 presses the latter arm, and consequently the arms $o^2 o^3$, back to normal position, the arm p' in its return movement lifting or turning the rack-hook, thus permitting the 45 racks h and i to fall. The fall of the same is limited by the arms h' and i' engaging the snails b and c . By this lifting of the rack-hook l the arbor l^2 has also been turned, and with the same the forked arm having the 50 members $t' t^2$, and the end of said member t^2 moved out of the reach of the fly v . The pinion for the striking-train has been released and the gathering-pins arbor q is turned. As soon as the gathering-pallet begins to move the pin q' pushes the arm p^2 aside, 55 whereby the hook of arm p' is lifted out of engagement with the pin l^4 , and the rack-hook l , owing to the spring l^3 , falls back until arrested by its forward end striking the quarter-rack i . The gathering-pallet lifts the quarter-rack by the aid of the pin q^2 , and the quarter-rack is held in a raised position by the ex-

tremity of the rack-hook. After the last quarter strikes, the rack-hook l falls forward until the pin l' of the same is stopped by the hour-rack. 70

In order that the quarter-hammers may still be lifted after the lifting of the rack for the last stroke, the rack-hook is temporarily arrested, thus arresting the arms $t' t^2$, which move with said rack-hook, by arm m , which falls into the path of the pin m' , fixed to said rack-hook. The continued movement of the arbor q brings the pin q^2 into engagement with and lifts out the arm m from engagement with pin m' , and the rack-hook falls into the position shown. Now as pin q' of the gathering pallet or tumbler lifts the hour-rack step by step it is held against returning by the bolt or pin l' until the said rack is completely lifted also, in which operation the arm m , in combination with the pin m^2 , renders the lifting of the hammer for the last stroke possible when this last stroke is due to fall. 85

It will be understood that the hour-rack is 90 lifted directly during the lifting of the quarter-rack one step each time the pin q' engages a tooth thereof; but having no support it drops back again as soon as the pin q' releases the same. During this time the member t' of the forked arm holds the bar y for operating the hour-hammer raised and therefore out of the path of the pin u . After the last stroke the rack-hook falls into its normal position, and the member t^2 of the forked arm engages 100 the fly-wheel and arrests the same, thus stopping the striking mechanism. During this time the lever having the three arms $n' n^2 n^3$ has remained at rest, having been held against its supporting-pin n^4 by means of the spring o^4 , as the foregoing, described as the ordinary strike. 105

In order to detach the striking mechanism, the arm p' of the angle-lever $p' p^2$ is raised by means of the pin on the piece s' , whereby this 110 arm is moved out of the line of movement of the pin l^4 of the rack-hook, and the latter will not, therefore, be lifted on the depression of the arm o' by the arm of the piece d , and the striking-train cannot, therefore, operate. 115

As will be seen from the foregoing, no ratchet-detent takes place in the present striking-work. In order to obtain as correct a time as possible in the repeating operation, 120 it is necessary to arrange the striking mechanism in such a manner that the full succeeding quarter be repeated five minutes before it is due on the termination of the quarter last struck. 125

In order that the quarter-rack may not rest between two steps or grades of the snail, or half on one step and half on the other, or when the termination of one quarter and the beginning of the succeeding quarter is reached, the 130 transition of one quarter to the other, which is ordinarily situated in the ratchet-detent, is achieved suddenly. For this purpose the quarter-snail b is loosely set on the center

arbor. On the back of the same is a four-part pinion-wheel *e*, which engages with its rounded parts into the eight-spoked star-wheel *f*. The latter is held by a spring-pressed detent *g*. On the snail, between two arms of the piece *d*, is a pin *e'*, controlled by these arms. When the center arbor *a* is turned, the piece *d*, which actuates the arm *o'*, turns with the arbor. As soon as this piece *d* reaches the pin *e'* it carries along the snail *b* and the four-part star *e*, fixedly connected therewith. Through this star-wheel *e* the eight-spoked star-wheel is turned and the roller-detent *g* is pressed back against the tension of its spring. As soon as this wheel has turned sufficiently to bring more than half of the point of one ray or spoke thereof past the detent said detent is pressed entirely into the next space or interstice by means of the spring *g'*. By this means the star-wheel *e*, and therewith the snail *d*, is moved by starts or jerks, as the steps or grades of the snail come over the point on which the quarter-rack arm *i* falls. This start, jolt, or jerk takes place five minutes before every succeeding quarter and takes the place of a warning or ratchet detent.

As aforesaid, the hook or arm *r'* holds fast the hour-rack at the appropriate position of the part *s*, so that this hour-rack cannot fall, and accordingly the hours cannot be repeated. In order to repeat, nevertheless, the hours at the last quarter, it is necessary to release this stop. For this purpose two pins *f'* are provided on the star-wheel *f*, which accomplishes one revolution every two hours, which pins press against a nose or lifter of the arm *r''* and lift it so far that in the release of the striking-train the hook *r'* has been pushed aside by the pin *h*. The spring *r* restores the engagement of the hook with the pin *h* before expiration of the next quarter. This is the ordinary strike, as before described.

In order to make the striking mechanism repeat at any time, the cord attached on the arm *n* of the lever pivoted at *n* is pulled. Thereby the rack-hook *l* is lifted by the arm *n*, so that the racks can fall and the fly is liberated. At the same time the pin *n* lifts the arm *r* of the lever pivoted at *r*, which tilts the arm *r'* and releases the hour-rack, so that both the quarters and the hour are struck in repeating. In this operation, when the striking-train has been released about five minutes before the quarter terminates, this quarter will not be again repeated at its completion and the release by hand moves the lever having the arms *n' n'' n'''* to the right, carrying the lever having the arms *o' o'' o'''* therewith, and the arm *o'* is disengaged from *d*; but as the spring *o* sets the arm *o'* horizontally, it remains out of gear when it returns after the repeat, and the arm *d* should press thereon and tilt the same to release the quarter. In this way it might occur that the clock would not strike automatically during more than twenty minutes. To

avoid this and to insure striking of all quarters independently without the repeating effecting the same, the arrangement shown in Figs. 9 and 11 is provided. In this arrangement the two three-armed levers are mounted on a common pivot. In addition the arm *p'* is provided with an angular extension *p*, the horizontal arm of which has an acute-angled notch. A pin *a* on an arm *a* pivoting around *a'* engages with this notch, and in this operation this arm is brought to its normal position by a spring *a*. When the arm *o'* is pressed down by an arm of the piece *d*, the nose of the extension *p* will engage with the pin *a* simultaneously with the engagement of the nose of the arm *p'* into the pin *l* of the rack-hook *l*. When the striking mechanism is released by hand, the angle-lever having the arms *p' p* is prevented from moving around with the lever having the arms *n' n''* and *n'''* by the pin *a*, so that the arm *o'* is not disengaged from the arm of the piece *d*. Thereby the operation of the arm *o'* by the arm of the piece *d* at the completion of the quarter, and hence the automatic striking, is assured. The pin-wheel *u*, which carries these pins *u*, is one of the transmission-wheels of the gearing arrangement of the striking mechanism to the fly. The pin *u* presses against the sliding bars when they are in the path of the same and resting upon the bolt or pin *t*, and the arbors *w w' w''*, which support the hammers, are thus turned as the sliding bars are moved by means of the arms *x x' x''*, so that the hammers are lifted for the strike.

I claim as my invention—

1. In combination, the hands-arbor, the hour and quarter-hour snails fixed thereto, the hour and quarter counter-racks, the pivoted supports for said racks, the fly-wheel, the hammer, and hammer-operating bars with means for operating the same, means for shifting said bars to prevent the operation to actuate the hammer and for arresting said fly-wheel, and a pivoted lever operated from said arbor and a lever carried thereby adapted to engage said support to remove the same from said racks and to release said fly-wheel and to shift said bars, substantially as described.

2. In combination, the arbor, the quarter-hour and hour snails fixed thereto, the counter-racks, the supports therefor the hammers, the means for operating the same controlled by said counters, means for removing said supports at the quarter-strike, a supplemental support for said hour count-rack alone and means for automatically removing the same for the hour-strike, substantially as described.

3. In combination, the arbor, the quarter and hour snails, the counter-racks, the supports therefor the hammers, with means for operating the same controlled by said count-racks, means for removing said support at the quarter-hour strike, a supplemental sup-

port for the hour-rack comprising a pivoted lever having one arm projecting into proximity to said arbor and means for tilting the same to release said hour-rack, substantially 5 as described.

4. In combination, the quarter-hour and hour snails, the arbor carrying the same, the count-racks, the supports therefor, the hammers with means for operating the same controlled by said racks, the extension from said hour-rack, the pivoted lever having one arm engaging therewith to support said rack alone and means for tilting a second arm of said lever to release the first arm from said extension, substantially as described. 15

5. In combination, the quarter-hour and hour snails, the arbor carrying the same, the count-racks, the supports therefor, the hammers with means for operating the same, controlled by said racks, the extension from said hour-rack, the pivoted lever having one arm engaging therewith to support said rack, and means automatically operating for tilting a second arm of said lever to release the first 25 arm from said extension, substantially as described.

6. In combination, the quarter-hour and hour snails, the arbor carrying the same, the count-racks, the supports therefor, the hammers with means for operating the same controlled by said racks, the extension from said hour-rack, the pivoted lever having one arm engaging therewith to support said rack and means manually operated for tilting a second 35 arm of said lever to release the first arm from said extension, substantially as described.

7. In combination, the hour and quarter-hour snails, the arbor carrying the same, the count-racks, the pivoted support therefor, the 40 hammer and sliding arms for actuating the same, the fly-wheel, the forked arm fixed to the racks support arbor, the member of said fork being adapted to control said sliding arms and said fly-wheel, a lever having one of its

arms extending into proximity to the snail-arbor, and means carried by said arbor adapted to tilt said arm and a second lever carried by a second arm of the first lever adapted to engage said support to remove the same from said racks and release said fly-wheel 45 and position said sliding bars, substantially as described.

8. In combination, the hour and quarter-hour snails, the support common to the same, the hour-rack the independent support for 50 the hour-rack, the hammer with means for operating the same controlled by said racks and the lever adapted to be tilted manually said lever having one arm adapted to press the common support to move the same from 55 beneath said racks, and a second arm adapted to release said independent support for the hour-rack, substantially as described.

9. In combination, the hour and quarter-hour snails, the count-racks, the supports 65 therefor, the hammer with means for operating the same controlled by said racks, the pivoted lever for removing the supports from said racks, and the means independent of 70 said pivoted lever for throwing said supporting removing means out of operation, substantially as described.

10. In combination, the hour and quarter-hour snails, the count-racks, the supports therefor, the hammers with means for operating the same, the independent hour-rack support, means for normally holding the same 75 in engagement, means for detaching the same automatically and the means for throwing the same out of operation, substantially as 80 described.

In witness whereof I have hereunto set my hand in presence of two witnesses.

JACOB GUTEKUNST.

Witnesses:

JACOB JOSEPH STEINER,
K. DREXLER.
